[57] ABSTRACT

At least one hollow rotatable drum is movable between a first and a second position in the latter of which it can receive and discharge its contents. First displacing means is provided for displacing the drum between its positions. Container means is movable between an upper and a lower position in which it is respectively located above and below the level of the drum when the latter is in the second position thereof. A hoist or similar means displaces the container means between the upper and lower positions thereof. Connecting means connects the interiors of the drum and the container means and enables gravity discharge of the contents of the drum to the container means when the drum is in the second position and the container means is in the lower position, and of the contents of the container means to the drum when the former is in the upper position and the drum is in its second position.

TUMBLER WITH DRUM TRANSFER APPARATUS

BACKGROUND OF THE INVENTION

The present invention relates generally to a transfer apparatus, and more particularly to an apparatus utilizing tumbler drums the contents of which need to be periodically transferred, completely or in part, out of the drum with the same or new contents being returned into the drum subsequently.

It is already known to provide apparatus of this type which basically involves a frame or support provided with at least two rollers or cylinders at least one of which is driven and on the circumferences of which there rests a drum which is hollow and which is rotated when the rollers rotate. The drum can be removed from the rollers and displaced onto or into a servicing device where the material to be tumbled, together with the tumbling means—such as balls, abrasive objects or the like—is charged or discharged from the drum, as the case may be. Liquid required for the tumbling operation may also be charged into or removed from the drum when the latter is moved to the servicing device.

The problem with the known constructions is that the tumbling means—which hereafter will be referred to as the tumbling balls, although other objects can also be used for this purpose—must manually be introduced into the drum when the latter is being charged. This is time-consuming, not only in terms of the period of time for which the drum is out of operation but also in terms of the labor required. Evidently, the larger the drum is, the more time will be needed in order to introduce the requisite quantity of steel balls or similar means into the drum.

Clearly, this is not entirely satisfactory and improvements in this field are therefore decidedly needed.

SUMMARY OF THE INVENTION

It is, accordingly, an object of the present invention to provide such improvements.

More particularly, it is an object of the present invention to provide an apparatus of the type in question which is not possessed of the disadvantages of the prior art and which is provided with these outlined improvements.

A concomitant object of the invention is to provide such an apparatus which permits rapid charging and discharging of the drum contents without requiring manual operations.

Still another object of the invention is to provide such an apparatus which despite the improvements is simple in its construction and reliable in its operation.

In pursuance of the above objects, and of others which will become apparent hereafter, one feature of the invention resides, in an apparatus of the type under discussion in the provision of at least one hollow rotatable drum movable between a first and a second position in the latter of which it can receive and discharge its contents. First displacing means are provided for displacing the drum between the positions thereof. Container means are movable between an upper and a lower position which are respectively above and below the level of the drum when the latter is in its second position. Second displacing means are provided for displacing the container means between the positions of the same, and connecting means are provided for connecting the interiors of the drum and of the container means whereby to enable gravity discharge of the con-

tents from the drum located at the second position to the container means located at the lower position thereof, and from the container means located at the upper position to the drum when the latter is in its second position.

With the apparatus constructed in accordance with the present invention, the balls or similar tumbling means accommodated in the drum will, when discharged therefrom, automatically move into and become collected in the container means. Subsequently when they are to be returned into the drum, the latter remains in its second position and the container means is raised to its upper position so that again the balls will move under the influence of gravity back into the drum, in neither case requiring for their displacement any manual aid. Moreover, the displacement of the tumbling balls between the drum and the container means, and vice versa, requires a fraction of the time which was heretofore necessary to effect the removal and return of the tumbling balls into the drum.

The apparatus according to the present invention preferably continues to utilize—as known from the art—a servicing device in which the drum is accommodated—to assume its second position—when it is to be discharged or charged. The container means and the associated components permitting it to be moved between its upper and lower positions is locatable in any desired relationship with respect to the servicing device as long as such relationship assures ready accessibility

25 to the servicing device and a drum contained in or on the same. According to a currently preferred embodiment the container means is to be located laterally of the axis of the drum and axially spaced from the latter. It is advantageous to provide the container means on its side facing the servicing device with an opening into which a free end portion of a conduit communicating with the interior of the servicing device, and therefore of a drum accommodated in it, can extend when the container means is in its lower position. To prevent interference of this free end portion with the movement of the container means to and from its upper position, the free end portion of the conduit may be made displaceable, for instance retractable out of the path of the container means.

40 According to the invention it is also advantageous, and assures a most simple return of the tumbling balls from the container means into the drum, when the lower portion of the container means is provided with a flexible hose which may be of rubber, plastic, metal or the like and which can be displaced between one position in which its open end communicates with the interior of the drum at the second position—either directly or indirectly via the servicing device—whereas in its other position the lower end is raised upwardly and the free end of the hose is connected to an upper portion of the container means to prevent undesired discharge of contents from the latter. The hose, particularly the outlet end portion thereof, may also be provided with a closure device, for instance a manually operating closure, which prevents undesired discharge until such time as the hose has been moved to a position in which its open end communicates with the drum to be charged.

45 It is also advantageous to still a further concept of the invention to mount the container means on vertical guide rails of a suitable frame or the like, and to provide a lift or hoist, preferably an electrically operated one, and in the upper portion of the frame, connecting

it with the container means so that the latter can be lifted and lowered between its upper and lower positions by the hoist.

The contents of the drum usually are comprised not only of the tumbling balls but also of a liquid. In order to make it possible to separate the tumbling balls from the liquid it is advantageous for the interior cross-section of the container means to be downwardly convergent and to provide the interior with a screen extending across it and preferably being removable for inspection or replacement. The lower portion of the container is then provided with a chamber in which liquid entering the container means together with the tumbling balls from the drum can collect and from which it can be discharged via a trough or similar discharge conduit. Thus, only the tumbling balls are retained in the interior of the container means, whereas the liquid runs off and can be discharged into a removal trough or conduit which preferably is so located that at least in the lower position of the container means the discharge conduit will discharge liquid into it. The spent liquid can then be freely removed and be replaced for the next charge with fresh liquid.

It is clear that the invention is applicable not only to an apparatus of the type discussed having a single drum, but also to an apparatus having a plurality of drums, such apparatus being known. In this case, the servicing device—which otherwise will be stationary on the machine—is made movable itself so that it can move to the various drums and receive each drum when it is ready for charging or discharging. The servicing device then transports the drum to a servicing station—corresponding to the second position of the drum—where the charging and discharging proceeds as outlined above.

It is also possible to provide an apparatus of this type with drums which are arranged in two superimposed rows, and to associate a movable servicing device with each of these rows of drums. In this case the drums of both rows can still be serviced for charging and discharging with one and the same container means, except that the container means must then be so constructed that it not only moves between an upper and a lower position but also an intermediate position. The upper position then is the position in which it can discharge to drums of the upper row, the intermediate position is the position in which it can receive material from drums of the upper row or discharge to drums of the lower row, and the lower position is the one in which it can receive material from the drums of the lower row. Evidently, the container means can be located either to the left or to the right of such an apparatus.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawing.

BRIEF DESCRIPTION OF THE DRAWING

FIG. 1 is a front view of an exemplary apparatus embodying the invention, illustrating the apparatus in one operative condition;

FIG. 2 is a view similar to FIG. 1 illustrating the apparatus in another operative condition;

FIG. 3 is a view similar to FIG. 2 illustrating the apparatus in a third condition;

FIG. 4 is a longitudinal section through components of the apparatus in FIGS. 1-3, with the components being located in the position shown in FIG. 2;

FIG. 5 is a longitudinal section through the container means of the illustrated apparatus;

FIG. 6 is a section taken on line 6—6 of FIG. 5; and FIG. 7 is a section taken on line 7—7 of FIG. 3.

DESCRIPTION OF THE PREFERRED EMBODIMENTS

Discussing the drawing now in detail, and referring firstly to FIGS. 1-3, it will be seen that the exemplary apparatus is provided with a frame having two spaced supports 10 and 12 which are rigidly connected by traverse members 14, 15 and 16. Mounted between the supports are two transversely spaced hollow cylinders 18 and 20 of which the former is driven by a non-illustrated drive mounted in the support 12, whereas the cylinder 20 is freely rotatable. Of course this relationship can be reversed and it is emphasized that the drive is not illustrated because it is entirely conventional and well known to those skilled in the art. A control console 22 is provided with switches and similar control devices 24 by means of which the drive of the driven cylinder can be operated.

30 A handwheel 26, combined with an RPM-indicator, permits selection of the desired rotational speed of the driven cylinder. In the illustrated embodiment the distance between the supports 10 and 12 is so selected that for instance five axially arrayed drums 20 can be supported on the circumference of the cylinders 18 and 20 with the circumference of their wheels 30 and 32.

35 The drums 28 are basically of known construction, being for instance provided with a drum body 34 of hexagonal cross-section having an opening 40 which is elongated and which can be closed by a cover 38 retained releasably in position by a retaining member 36. At the end faces of the drum wheels 30 and 32 there is provided centrally a pin 42 and 44 and these abut against spacer arms 46 which extend between consecutive ones of the drums.

40 The traverse member 16 is configurated as a liquid-removal trough whereas the traverse members 14 and 16 are configurated as rails for a servicing device which is identified in toto with reference numeral 48 and is displaceable longitudinally of the apparatus, being arrestable when it is in traverse alignment with the respective drums. The drive 48 comprises a carriage 50 having two spaced side walls 52 and 54, and the lower portion of the carriage 50 is configurated as a trough 56 into which the contents of the respective drum are to be discharged. A liquid removal conduit 58 is also associated with the trough 56 on the support, below the trough 16. In order to convey liquid flowing out of the drums into the trough 58, the trough 56 may for instance be provided at its left side with an outlet 60.

45 To charge the drums or discharge them they can be manually removed from the cylinders 18 and 20 and placed onto the carriage 50 of the drive 48, and during this movement the pins 42 and 44 will move onto an upper abutment face 61 on the side walls of the device 48 and move into engagement with a latching device 62 which retains them so that when the drum is subse-

quently turned in order to move its opening 40 into an upper position for filling or into a lower position for discharging, the drum cannot shift its position. A screen 64 covers the trough 56 and a hose 66 is provided on the drive 48 for introducing fresh water or other liquid required or desired into the interior of the respective drum.

It is emphasized that an apparatus such as has been described thus far is already known. The drums can be used with all kinds of tumbling aids, such as tumbling or abrasive bodies of various sizes and configuration, and water or other liquid may be added to the charge.

According to the present invention the apparatus is provided with means for permitting gravity charging and discharging of the contents of the drums. For discharging the drum contents in conventional manner the drum is placed onto the device 48 with its opening 40 facing downwardly, and the solid components of the drum charge will be retained on the screen 64 whereas the liquid runs off into the trough 58. According to the invention, however, container means 70 is provided which facilitates charging and discharging of the solid contents. These solids contents, such as steel balls or the like, are difficult and slow to handle for charging and discharging purposes if this is to be done manually. With the device according to the present invention, however, charging and discharging can be carried out rapidly, conveniently and without necessitating any manual handling by an operator.

The container means according to the present invention comprises a support 76 having two parallel uprights 72 and 74 or rails which are connected at their upper and lower ends so as to make the frame rigid and provide a stable preferably box-shaped support. The frame 76 is suitably connected to the upright 10 in this embodiment, preferably in a removable manner at the outer side thereof. Guide rails 78 and 80 are provided on the front side of the frame and a container 82 is displaceable vertically on the guide rails between an upper and a lower position. The guide rails 78 and 80 are preferably in form of hollow profile members which advantageously are of quadratic cross section and provided at their front side with a longitudinal slot 84 into which guide members 86 and 88 engage which are provided on the container 82 at the top and bottom regions in pairs. The outer ends of these members 86 and 88 are provided with double rollers 90 which engage with the rails. In the illustrated embodiment a chain 92 is connected to the container 82 and is associated with a hoist 96 provided on a supporting member 94 mounted in the upper portion of the frame 76. In this embodiment the hoist 96 is operated by means of an electromotor 98, controlled for instance via pushbuttons 100, and raises or lowers the container 82. For instance the pushbuttons may each control the operation of the electromotor in a sense making the container 82 move the entire distance from its lower position to its upper position, or vice versa. A further pushbutton may be provided to effect an emergency stop of the movement of the container, either in upward or downward direction, should the necessity arise.

FIGS. 5 and 6 that the lower portion of the container 82, whose cross-section is to be of downwardly convergent configuration is provided with a screen insert 102 which achieves just this purpose by cooperating with the downwardly and inwardly inclined front wall 104 of the container 82. Behind the inset 102 there is formed

a chamber 106 for collection of liquid which latter is discharged from the chamber 106 through an outlet 108 which, when the container 82 is in the lower position shown in FIG. 5, overlaps an edge portion 110 of a removal channel 112 to discharge into the latter. The channel 112 is provided with an outlet opening 114. A flexible hose 118 is provided which is connected with the lower end of the container 82 at 116, whereas the free end of the hose 118 is provided with a manually actuated closure cap 120 of a device 122. The end portion of the hose 118 can be releasably secured to the upper portion of the container 82 when not in use.

FIGS. 1 and 3 show that the movement of the container 82 in upward and downward directions is limited by limit switches or similar devices 124, 126 which may for instance be located at the front side of the member 74 at the appropriate levels. The container 82 is provided in the upper portion of its side walls with respective lateral openings 128 and 130 so that it can be positioned either to the left or to the right of a machine such as illustrated, as the case may be, or can be located in the middle between two such machines if it is to serve two such machines at the same time.

The container 82 is in the lower position, in which it is to receive contents from one of the drum, located at such a level that the outlet 60 of the carriage 50 extends into the facing opening 128 when the carriage 50 is in the position shown in FIGS. 2 and 4.

To introduce steel balls or similar means into the drums, the container 82 is first moved to its lower position shown in FIG. 1, and then receives the requisite quantity of steel balls or the like. Subsequently depressing of the pushbutton 100 will cause the container 82 to move to its upper position. Thereupon the device 48—which here is movable but could also be stationary if only a single drum were involved—is moved to the drum which is to receive a charge and is arrested, whereupon the drum is transferred from the cylinders 18 and 20 onto the carriage 50 of the device and is arrested as shown in FIG. 4. The drum is then moved to its second position—the first position being its position on the cylinders 18 and 20—by means of the device 48 until it reaches the location shown in FIG. 4 where the device is arrested. Now, and for instance after objects which are to be treated with the steel balls and also liquid if desired is introduced into the drum, the hose 118 is released from the upper end portion of the container 82 and its free end is inserted into the opening of the drum. Removal of the cap 120 now permits the steel balls to move from the container 82 through the hose 118 into the drum. When this is completed, having taken place under the influence of gravity alone, the drum is closed and returned to its first position resting on the cylinders 18 and 20, whereupon the next drum may be charged in the same manner, with the container 82 meanwhile having been returned first to its lower position shown in FIG. 4.

As this takes place, the contents of individually charged and continuously rotating drums may already have been sufficiently processed, so that a new drum—that is one to be discharged—can be placed into the device 48 which is then moved to the position shown in FIGS. 2 and 4 whereupon the drum is opened and its contents discharged. The objects which have been processed are retained on the screen 64, where in FIG. 4 they are designated with reference numeral 132 for exemplary purposes, whereas the balls 134 which have

also been discharged will pass through the openings of the screen 164 together with any liquid which may have been contained in the drum and enter into the container 82. The objects 132 are now removed from the device 48 and the drum is turned so that its opening faces upwardly. During this time, or subsequently thereto, the container 82 has been returned to its upper position and now the balls can be returned via the hose 118 by gravity in a brief time to the drum, with water or other liquid being added as desired via the hose 66. The turn-around time, that is the time required for discharging and recharging the drum, is thus extremely short and no manual intervention for removal or re-introduction of the tumbling balls or the like is required.

It is clear that the present invention avoids the disadvantages of the prior art and achieves the desirable advantages which have been outlined in the introductory portions of this specification.

It will be understood that each of the elements described above, or two or more together, may also find a useful application in other types of constructions differing from the types described above.

While the invention has been illustrated and described as embodied in a transfer apparatus, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, all such adaptations should and are intended to be comprehended within the meaning and range of equivalence of the following claims.

What is claimed as new and desired to be protected by Letters Patent is set forth in the appended

1. In an apparatus as described, in combination, at least one row of axially arrayed hollow drums, each of said drums being movable between a first and second position in the latter of which it can receive and discharge its contents; guide means for guiding said drums between said positions thereof; container means adjacent one end of said row and movable relative to said row between an upper and a lower position which are respectively above and below the level of a respective drum which is in said second position; displacing means for displacing said container means between said positions thereof; a transporting device mounted for movement along said row and operative for receiving a respective drum when the same is in said second position,

and for transporting said drum longitudinally of said row to and from a location adjacent said container means; and connecting means for connecting the interior of respective drums and said container means whereby to enable gravity-discharge of the contents from a drum which is located at said location and in the second position to the container means while the same is in the lower position, and from the container means while the same is in the upper position to a drum located at said location and which is in the second position.

2. In an apparatus as defined in claim 1, said drums having a common axis of rotation; and said container means being positioned laterally of said axis.

3. In an apparatus as defined in claim 1; and further comprising rotating means for rotating said drums about a longitudinal axis common to them.

4. In an apparatus as defined in claim 1, said connecting means comprising a conduit communicating with said servicing device and having a free end portion; and said container means having a side facing said servicing device and being provided with an opening communicating with said free end portion when said container means are in said lower position.

5. In an apparatus as defined in claim 1, said container means having a lower portion provided with a flexible hose having a free end section, an upper portion, attaching means for releasably attaching said free end section to said upper portion, and blocking means for blocking said hose against movement of material therethrough.

6. In an apparatus as defined in claim 1; further comprising frame means including upright guide rails and having an upper section; and wherein said second displacing means comprises lifting means provided at said upper section and connected with said container means for effecting displacement thereof along said guide rails between said upper and lower positions.

7. In an apparatus as defined in claim 6, wherein said lifting means comprises electric drive means.

8. In an apparatus as defined in claim 1, said container means comprising at least one container having an upper end and a lower end and having a downwardly converging interior cross-section a screen insert in the interior of said container, a chamber provided in the region of said lower end for collecting liquid run-off from the remainder of said container, and an outlet communicating with and projecting from said chamber.

9. In an apparatus as defined in claim 8; further comprising a collecting trough positioned so that said outlet discharges thereto at least when said container means are in said lower position.

* * * * *
